UNITED STATES PATENT OFFICE.

RICHARD BRADSHAW, OF TORONTO, ONTARIO, CANADA.

CHILD'S CRIB.

1,140,439.

Specification of Letters Patent. Patented May 25, 1915.

Application filed December 4, 1913. Serial No. 804,672.

To all whom it may concern:

Be it known that I, RICHARD BRADSHAW, of the city of Toronto, in the county of York, in the Province of Ontario, Canada, have invented certain new and useful Improvements in Children's Cribs, of which the following is the specification.

My invention relates to improvements in children's cribs and the object of the invention is to devise a simple, cheap and durable automatic latching device for securing the vertically movable gate forming the side of the crib in its raised position and such as may be formed out of a single piece of metal and such as cannot be released by the child within the crib and it consists essentially of a latching device having a forked end designed to extend to each side of the crib post having inturned portions extending into and swung in diametrically opposite holes in the crib post, such piece extending normally in an upward inclined direction and bearing at its upper end beneath the top bar of the side gate of the crib as hereinafter more particularly explained by the following specification.

Figure 1, is a perspective view of my crib showing the gate in its normal or latched position in full lines and its lower or down position by dotted lines. Fig. 2, is an enlarged perspective detail of my latching device in the latched position. Fig. 3, is a similar view to Fig. 2 showing the parts in the unlatched position. Fig. 4, is a vertical section through Fig. 2. Fig. 5, is an enlarged perspective detail of the latching piece.

In the drawings like letters of reference indicate corresponding parts in each figure.

A is my crib provided with the usual ends A¹ and A² having corner posts A³ and A⁴. A⁵ are diametrically opposite holes formed in the crib post.

B are the guide bars for the vertically movable gate secured to the corner posts A³ and A⁴ in the usual manner. B¹ is the crib gate provided with the usual upper and lower bars B² and B³ having end eyes B⁴ and B⁵ through which the guide bars B freely extend. C is my latching piece provided with a forked portion C¹ extending to each side of the corner posts and terminating in inturned portions C² extending into diametrically opposite holes A⁵ of the corner posts A³ and A⁴. The outer side of the upper end of the latch is provided with

an outwardly extending lip C³ by which the latching piece may be swung upwardly and an arc-shaped recess C⁴ designed to fit against the side bars B.

It will also be noticed that the latching piece C is curved slightly upwardly from end to end thereby providing for a stronger grip against the guide rod B.

It will thus be seen that when it is desired to open the crib gate to place the child within the crib all that it is necessary to do is to place the thumb under each latch lip C³ so as to spring the latching piece C upwardly on its pivot formed by the inturned portion C² and free of the upper ends B². The gate, of course, during this operation rises slightly upwardly. The gate may then be lowered. As soon as the ends of the bar B² have passed the latching piece in moving to its open position the latching piece may be released so as to rest in an incline position against the guide bars B. When it is desired to close the gate all that it is necessary to do is to raise the gate vertically until the upper ends contact with the latching piece swinging the frame upwardly allowing the upper ends to pass. As soon as the upper ends have passed the latching piece, such piece drops downwardly by means of gravity against the guide bars B and beneath the upper ends B⁴ thus securely locking the gate from downward movement.

From this description it will be seen that I have devised a very simple latching device for the side gate of a child's crib which will automatically latch as the gate is raised to its closed position and which may be easily released from the outside of the crib and which will be cheap, strong and durable.

What I claim as my invention is.

1. An automatic lock for children's cribs comprising a corner post having a vertical rod suitably supported in proximity thereto, a side gate the upper bar of which is provided with an eye through which said vertical rod extends, and a latch provided with a forked lower end having trunnions fitting into holes in the post and forming a pivot for the latch, and the upper end provided with a recess forming a jaw to normally straddle said vertical rod and bind on the same to support the eye of the top bar of the gate, and yet when swung back from the rod upon the top bar of the gate being

raised will permit the eye to descend on the rod to the lowermost position as and for the purpose specified.

2. In a fastener for sliding side cribs, the combination of a crib post, a guide rod supported in spaced relation therefrom, a projection from the crib side slidingly mounted on said guide rod and a latch having its lower end bifurcated and pivotally connected to opposite sides of the post and its up-

per end normally leaning against said guide rod and adapted in such position to support the projection thereabove and to be swung back from said guide rod and allow said projection to pass thereon.

RICHARD BRADSHAW.
